UNITED STATES PATENT OFFICE.

THOMAS J. STURTEVANT, OF WELLESLEY, MASSACHUSETTS, ASSIGNOR TO STURTEVANT MILL COMPANY, OF BOSTON, MASSACHUSETTS, A CORPORATION OF MASSACHUSETTS.

ELEVATOR.

1,391,703.

Specification of Letters Patent. Patented Sept. 27, 1921.

Application filed February 23, 1918. Serial No. 218,647.

To all whom it may concern:

Be it known that I, THOMAS J. STURTEVANT, a citizen of the United States, and resident of Wellesley, county of Norfolk, 5 and State of Massachusetts, have invented an Improvement in Elevators, of which the following description, in connection with the accompanying drawings, is a specification, like characters on the drawings representing like parts.

The invention hereinafter described relates to means for adjusting the guide wheels of bucket belts for elevators, and more particularly to means for adjusting 15 the guide wheel for the lower end of a bucket belt mounted adjacent the base of the boot or casing of an elevator.

The base of the boot is liable to become clogged by accumulation of material there- 20 in; obstructions occasionally enter the boot and tear a bucket or buckets from the belt; the belt becomes stretched and worn in use, and occasionally breaks, thereby causing the belt and buckets to drop and pile in a 25 jumbled mass at the base of the boot. These conditions demand that convenient access should be had to the parts for the purpose of cleaning, removal, replacement, adjustment and repair thereof in order that the 30 elevator may be promptly put again in working order. To accomplish this the lower guide wheel should be quickly adjustable to slacken the belt, to lift said wheel up out of the way to allow access to the base of 35 the boot, and to return the wheel with proper adjustment to its normal working position.

Heretofore it has been customary to adjust the lower guide wheel shaft by means 40 of screws connected to the journal boxes at opposite sides of the elevator boot, said screws being usually held in different positions of adjustment by nuts or other locking means. These screws have been found 45 to be objectionable for various reasons. Among others, the adjustment of the shaft by the screws is necessarily a slow operation; it is necessary to apply a tool to release and reset the lock nuts before and after 50 every adjustment; the screws and nuts are liable to become rusted and so locked together that ready release thereof is impossible, and it is difficult to obtain equal adjustments of the screws at the opposite sides

of the elevator boot and correct adjustment 55 of the guide wheel shaft.

The present invention, among other objects, aims to provide a simple and effective device whereby the guide wheel may be easily and quickly adjusted; the journal 60 boxes for the shaft for said wheel may be given equal adjustments; and the boxes therefor may be readily locked in position and released as desired.

The character of the invention may be 65 best understood by reference to the following description of one good form thereof shown in the accompanying drawings, wherein:

Figure 1 is a side elevation of an elevator 70 embodying the invention;

Fig. 2 is an end elevation of the elevator shown in Fig. 1;

Fig. 3 on an enlarged scale is an end elevation of the lower part of the elevator 75 boot or casing showing the means for adjusting the lower guide wheel for the bucket belt, a portion of the construction being broken away to disclose parts beyond the same;

Fig. 4 is a side elevation of the lower portion of the boot or casing and the means for adjusting the lower guide wheel for the bucket belt;

Fig. 5 is a side elevation of the notched 85 hand wheel and the locking dog co-operating therewith; and

Fig. 6 is a horizontal section taken on line 6—6 of Fig. 4.

Referring to the drawings, the elevator 90 shown therein as an exemplification of the invention comprises a boot or casing 1 (Figs. 1 and 2) having a head 3 mounted thereon. The materials to be elevated may be introduced into the boot adjacent the base thereof 95 through a hopper 5, and the materials after being elevated may be delivered through an opening 7 to a chute (not shown) for conducting the materials to the point desired. Convenient access may be had to the lower 100 portion of the boot on opening a door or panel 9 which may be secured by latches 11 to the body of the boot.

To elevate the materials from the base of the boot to said head, a belt may be provided, in the present instance of the invention, in the form of a sprocket chain 13 carrying buckets 14 and guided by an upper

- sprocket wheel 15 and a lower sprocket wheel 17. The upper sprocket wheel is mounted fast on a shaft 19 journaled in bearings in the head, said shaft being driven by a gear 21 (Fig. 2) fast thereon meshing with a pinion 23 fast on a counter shaft 25 journaled in bearings on said head, and having a pulley 27 fast thereon adapted to be driven by a belt from any suitable source of power.
- 10 The lower sprocket wheel is mounted fast on a shaft 29 projecting through elongated openings 31 (Fig. 6) in opposite sides of the boot, said shaft being journaled in boxes 33 and confined against longitudinal movement 15 therein by collars 35 fast on the ends of said shaft. Guide frames 37 may be provided adjacent the shaft openings 31, and have flanges 39 secured by bolts 41 to the outer faces of opposed sides of the boot. These 20 frames may be formed to present inturned flanges 43 projecting into grooves 45 in said boxes and serving as guides therefor. To prevent escape of materials through the elongated openings 31, covers 47 may be 25 provided having their vertical edges projecting in grooves 49 formed between the guide frames 37 and the margins of the sides of the boot adjacent the openings 31. The covers are apertured to receive the shaft 29, 30 and to prevent the escape of dust between said shaft and apertures, rings 51 may be provided having flanges 53 riveted to said covers, said rings being formed to present recesses for receiving suitable packing material 55 held in said recesses by said covers. The covers move up and down with the shaft 29 when the latter is adjusted by means to 35 be described. To prevent wear between the covers and the shaft, the rings 51 secured to 40 said covers may have arcuate flanges 57 (Fig. 3) adapted to rest upon the upper sides of the journal boxes for said shaft, the construction being such that the shaft is relieved from the weight of the covers and 45 rings.
- The means for moving or adjusting the journal boxes along their guides, in the present instance of the invention, comprises bars 59 having their lower ends pivotally connected by bolts 61 with ears 63 projecting upwardly from said boxes, and their upper portions formed to present racks 65 meshing with pinions 67 fast on a shaft 69 journaled in bearings in upper extensions of 50 the guide frames 37, referred to. The racks 65 are held in mesh with the pinions by guides 71 (Fig. 4) projecting from the frame extensions and having plates 72 secured by bolts 73 to said guides.
- 60 Suitable means may be provided for rotating the pinions 67 and the shaft 69. To accomplish this, in the present instance, a hand wheel 75 is mounted fast on one end of said shaft, where it is conveniently accessible 65 to the operator. On rotation of this hand

wheel, the pinions will be rotated and the rack bars 59 will be simultaneously moved upward or downward and move the bearing boxes equally upward and downward according to the direction of rotation of the 70 hand wheel.

Suitable means is provided to hold the bearing boxes in their different positions of adjustment. In the present form of the invention, this means comprises a series of 75 notches 77 (Fig. 5) on one face of the rim of the hand wheel, said notches being tapered radially toward the axis of said wheel. Coöperating with these notches is a lock lever 79 having a hub 81 fulcrumed on a bolt 80 mounted in a boss 85 projecting laterally from one of the frame extensions, referred to. The head of said bolt is seated in a counter bore 87 in said boss, and the hub of the lever is confined between said boss and a 85 nut 89 (Fig. 3) threaded on the outer end of said bolt and locked by a cotter pin 91. One end of the lever 79 is formed to present a wedge-shaped tooth 93 (Fig. 5) adapted to enter any of the tapered notches 77 in said 90 wheel. The opposite end of said lever may be provided with a weight 95 which tends to maintain the tooth in any of said notches according to the adjustment of said wheel.

In operation, the upper guide wheel 15 being driven as described, the belt will travel and cause the buckets 14 to elevate materials from the base of the boot to the head thereof and deliver the materials in a manner well understood in the art. If, for example, the 95 belt should break and allow the belt and buckets to drop into the base of the boot, the lower guide wheel for the belt may be easily and quickly raised up out of the way. To accomplish this, it is merely necessary to 100 rock the lock lever 79 from its full line position to its dotted line position shown in Fig. 5, thereby releasing the hand wheel. Then the latter may be grasped by the operator and rotated, thereby rotating the pinions 105 and lifting the racks, boxes and lower shaft upward to the point desired. Then the lock lever is returned to its full line position shown in Fig. 5, thereby locking the hand wheel and holding the parts in their raised 110 position. Release of the latches 11 will permit removal of the door 9 and allow convenient access to the belt and parts in the bottom of the boot. After the necessary 115 repairs have been made, the lock lever is released and the hand wheel rotated to cause the boxes, shaft and lower guide wheel to be adjusted downward to their normal positions. If desired, the hand wheel may be released to allow the boxes at the opposite 120 sides of the boot to gravitate downward and allow the lower guide wheel to automatically seat itself in the loop of the belt suspended by the upper guide wheel and give the belt the tension required. Then the lock lever is 125 130

rocked to again lock the hand wheel against rotation. The door 9 may be then closed and the elevator will be in condition to resume operation.

- 5 The racks and pinions furnish very advantageous means for effecting quick adjustment of the boxes, and since the pinions are on the same shaft, equal adjustment of both boxes are assured without attention on 10 the part of the operator. The adjusting device is such that no tools are required to effect the adjustment, and the device is always in condition to enable prompt adjustments. As a consequence, repairs may be quickly 15 made with a minimum loss of time, thereby materially adding to the usefulness of the apparatus.

It will be understood that the invention is not limited to the specific embodiment shown, 20 but that various deviations may be made therefrom without departing from the spirit and scope of the appended claims.

What is claimed is:

1. In an elevator or the like, the combination 25 of a pair of spaced oppositely disposed frames, bearing boxes mounted to slide vertically in the frames, a shaft journaled in the bearing boxes and having a vertically disposed conveyer belt passed thereabout, 30 and means for adjusting the shaft and securing it in different positions of adjustment, comprising a cross shaft journaled upon said frames, a rack slidably mounted upon each frame and each rack having an

end thereof pivotally secured to one of the 35 bearing boxes, gears upon the cross shaft meshing with the respective racks, a hand wheel fast on the cross shaft and having wedge-shaped locking notches formed therein, and a gravity operated dog pivotally 40 mounted upon one of said frames and having a tooth shaped to conform to and enter automatically into firm locking engagement with the wedge-shaped notches.

2. In an elevator or the like, the combination 45 of a pair of spaced oppositely disposed frames, bearing boxes mounted to slide vertically in the frames, a shaft journaled in the bearing boxes and having a vertically disposed conveyer belt passed thereabout, 50 and means for adjusting the shaft and securing it in different positions of adjustment, comprising a cross shaft rotatably supported by the frames, a pair of racks secured to the bearing boxes and slidably 55 mounted upon the respective frames, a pair of gears fast on the cross shaft and meshing with the racks, a hand wheel fast on the cross shaft and having wedge-shaped locking notches formed therein, and a gravity 60 operated dog having a tooth shaped to conform to and enter automatically into firm locking engagement with the wedge-shaped notches.

In testimony whereof, I have signed my 65 name to this specification.

THOMAS J. STURTEVANT.
